FORGING DEVICE

Dudley W. Hart and Edward F. Wickens, Phil-
lipsburg, N. J., assignors to Ingersoll-Rand
Company, Jersey City, N. J., a corporation of
New Jersey

Application February 11, 1938, Serial No. 189,958

2 Claims. (Cl. 78—13)

This invention relates to forging devices, and more particularly to the arrangement of the dies used on drill sharpening machines for imparting a desired conformation on a blank, as for example the threads on a drill rod used in connection with detachable drill bits.

One object of the invention is to avoid imperfections in the forged article.

Another object is to avoid the occurrence of error in the forged article as a result of an erratic action by the forging machine when its parts become worn unduly.

Other objects will be in part obvious and in part pointed out hereinafter.

In the drawing accompanying this specification and in which similar reference numerals refer to similar parts,

Figure 1 is a side elevation of so much of the forging device and so much of a drill sharpener as will serve to illustrate the invention,

Figure 2 is a similar view, somewhat enlarged, and broken away,

Figure 3 is a transverse view taken through Figure 1 on the line 3—3 looking in the direction indicated by the arrows, and

Figure 4 is a plan view taken through Figure 1 on the line 4—4.

Referring more particularly to the drawing, 20 designates a forging machine shown as a drill sharpener and comprises a base 21 and a head 22 which is reciprocable in a vertical plane with respect to the base 21.

The drill sharpener may be of a well known type that is actuated by pressure fluid and has a cylinder 23 in the base to accommodate a piston 24 which is connected to the head 22 by a rod or rods 25 slidable in the base. The pressure fluid employed for actuating the piston 24 may be distributed to the cylinder 23 by suitable valve mechanism 26 actuated by a manually operable lever 27.

In accordance with the practice of the invention, the base 21 is provided with a recess 28, in its upper surface, to receive a die block 29 in the form of a rectangular member. A locating pin 30, seated in the base 21, engages the block 29 and a clamp plate 31 and a screw 32 serve to clamp the block 29 securely to the base 21.

Within the die block 29 is a recess 33 of rectangular shape to receive top and bottom thread-forming dies 34 and 35, respectively. Both dies are fitted for slide movement in the recess 33 but with sufficient accuracy to preclude misalignment of the dies with respect to the side surfaces

of the recess 33 whereby they are guided. In the confronting surfaces of the dies are depressions 36 which are developed to the form which it is intended to forge on the work, this being in the present instance, a thread 37 on a rod 38.

To the end that the top die 34 may be conveniently raised from the work between blows of the head 22 so that the rod 38 may be shifted to different positions the die 34 is provided at its ends with pins 39 which are slidable in slots 40 in the sides of the die block 29. The pins 39 extend beyond the ends of the die block, and on the head 22 is a plate 41 which, during the reciprocations of the head 22, strike against the top die 34 and carries a pair of lifters 42. The lifters are in the form of hooks lying on opposite sides of the die block 29 and of such length that they will engage the pins 39 at an intermediate point in the up-stroke of the head for lifting the top die 34 from the work.

The plate 41 is preferably readily detachable from the head 22 and is accordingly secured in position by a clamp member 43 which is forced against the plate 41 by a screw 44.

To the end that the rod 38 may be conveniently locked in the correct position with respect to the forming dies, the drill sharpener is equipped with suitable chuck mechanism 45 supported by rods 46 carried by the die block 29. The chuck 45 comprises a guide member 47 mounted on the ends of the rods 46 and having a bore 48 in which is a thread 49 of the same lead as the thread 37 to engage the thread 50 of a sleeve 51 threaded into the bore 48.

The bore 52 within the sleeve 51 and through which the rod 38 extends is of somewhat larger diameter than the rod, and in order to maintain the rod 38 coaxial with the forming portions of the dies a pair of rests 53 are threaded into the sleeve 51 and extend into the bore 52 to support the rod 38. The rests 53 are readily adjustable to accommodate rods of different diameter and are locked in position by nuts 54 threaded on the rests 53 and seating against the periphery of the sleeve 51. On the outer end of the rests 53 are grip members 55 which may be grasped for rotating the sleeve.

The sleeve is, moreover, provided with clamping screw 56 which may be a replica of the rests 53 but lacks the lock nut 54. The screw 56 is likewise provided with a grip member 55 and serves the function of locking the rod 38 securely against the rests 53.

In the operation of the device, and assuming

that the head 22 is in its uppermost position illustrated in Figures 1, 2 and 3, the heated end of the rod is inserted through the sleeve 51 and disposed upon the bottom die 35. The set screw 56 is then manipulated to clamp the rod securely in position. Thereafter the valve 26 is shifted, by means of the lever 27, to admit pressure fluid into the cylinder 23 for actuating it downwardly. During this movement of the piston the head 22 will strike against the top die 34 and forge the threads 37 on the rod. After delivery of the blow to the top die the valve mechanism 26 is next manipulated to deliver pressure fluid beneath the piston 24 for raising the head 22.

15 During the upward movement of the piston and shortly before it reaches its uppermost limiting position the hooks 42 engage the pins 39 and lift the top die 34 from the work. The rod 38 may then be rotated to a new position on the bottom die 35 by rotating the sleeve 51. The valve mechanism 26 is then again operated to cause the piston 24 and the head 22 to descend.

20 At an intermediate point in the descending movement of the head 22 the top die 34 will contact the work and remain there in readiness to receive the blow of the head 22. This operation is repeated as often as may be required to complete the forging of the thread 37.

25 As will be readily observed from the foregoing description there is no permanent connection between the top die 34 and the element, in the present instance the head 22, whereby it is actu-

ated. The top die is guided entirely by the die block, and in view of these facts any tilting or misalignment of the head 22 as a result of wear on the elements guiding and supporting it will not be transmitted to the top die for the reason that the head is disengaged from the die 34 before the blow is delivered against said die. 5

We claim:

1. In a forging device, the combination of a base and a head reciprocable with respect to the base, a stationary bottom die in the base, a top die to receive the blows of the head and being slidable in the base, and lifters affixed to the head to move into engagement with the top die at an intermediate point in each alternate stroke of the head for lifting the top die from the bottom die. 10

2. In a forging device, the combination of a base and a head reciprocable in a vertical plane with respect to the base, a stationary bottom die in the base, a top die to receive the blows of the head and being slidable in the base, lifters carried by the head to move into engagement with the top die at an intermediate point in the stroke of the head for lifting the top die and to move out of engagement with the top die during the descending movement of the head to deposit the top die upon the work, and means to maintain the lifters constantly in position to engage the top die. 15
